RAILWAY CAR TRUCK STRUCTURE

Edwin G. Busse, Chicago, Ill., assignor to Chicago Railway Equipment Company, Chicago, Ill., a corporation of Illinois

Application March 25, 1935, Serial No. 12,840

20 Claims. (Cl. 188—210)

This invention relates to railway car trucks and more particularly to means for mounting thereon brake beam guards, guides, or support structures.

There is an increasing tendency in railway truck construction to decrease the weight of the truck by eliminating the spring plank which usually extends between the side frames and mounts the bolster springs and, frequently, mounts the brake beam supports and safety guards. In some old trucks the portions of the spring planks intermediate the side frames are being cut out, the end portions of the spring plank, or similar structure, being retained and utilized as seats for the bolster springs and for attachment of a transverse tie bar extending between the side frames.

An object of the present invention is to mount brake beam guard, guide, or support structure upon the spring seating structure.

Another object is to secure the end of the spring plank or bolster spring seat to the side frame so as to maintain the parts assembled when the bolster springs are removed.

A more detailed object is to attach a brake beam guard, guide, or support device to a ledge or web projecting inwardly from the truck side frame, or other part, so as to support the device without relying upon rivets or similar attaching elements.

These objects and other more detailed objects hereafter appearing are attained by the structures illustrated in the accompanying drawings, in which—

Figure 1 is a transverse sectional view through the side frame of a railway truck embodying one form of the invention.

Figure 2 is a top view of the structure in Figure 1 with the bolster springs omitted.

Figures 3, 4, 5, 6, 8, 11, 12, 14, 15, 16, 17, and 18 are views similar to Figure 1 but illustrating various modifications.

Figure 7 is a partial top view of the structure in Figure 6.

Figure 9 is a top view of railway truck parts illustrating a different form of brake beam safety guard device.

Figure 10 is a transverse vertical section taken on the line 10—10 of Figure 9.

Figure 13 is a top view of the structure in Figure 12.

Figures 1 and 2 show the lower center portion 1 of a well known form of railway truck side frame having a central opening for receiving the bolster springs 9 and the end of the bolster (not shown). Framing member 1 includes a substantially horizontal web 2 projecting laterally in each direction

from the side frame, as at 3 and 4. Mounted on top of the web 2 is a channel member including the vertical flanges 5 and horizontal web 6, recessed as at 7 for interengagement with the boss 8 on the framing web 2 for holding the channel member in position. Seated on the web 6 are the coil springs 9 for supporting the end of the bolster (not shown) as is well known. The channel spring seat member may be conveniently formed from the end portion of an ordinary channel spring plank.

Located inwardly of the side frame member 1 is the bracket 10 mounting the brake beam guard, guide, or support strap 11 between the flanges 12 by means of pins, one of which is shown at 13. The member 11 is disposed inwardly, as at 14, and then longitudinally for association with the brake beams.

Bracket 10 includes the outwardly projecting jaws 15 receiving therebetween the inner extremity of ledge portion 4 of the horizontal framing web 2 and a lip 16 extending around and over the inner extremity of the channel web 6 and secured thereto by rivets 17. The web 6 is bulged at 18 to accommodate the upper bracket jaw 15. The guard, guide, or support member and its supporting bracket are wholly carried by the jaws 15 and lip 16, the rivets 17 functioning solely to maintain the assembly.

At the outer extremity of the framing horizontal web 2 is a lip 19 hooked over the corresponding extremity of channel web 6 to assist in maintaining the spring seating channel in position in case the bolster springs are removed.

In Figure 3, channel spring seating member 20 rests upon the horizontal web 21 of the side frame bottom member 22, as in the previous form. The guard, guide, or support bracket 23 is attached to the inner extremity of the channel 20 by means of a rivet 24 and a lip 25 hooked over the inner extremity of the channel horizontal web. A short lug or rib 26 is provided for attachment of the side frame tie bar 27 which tends to maintain the channel 20 in position on the side frame web 21. No hook is provided at the outer extremity of the seating channel for stabilizing the assembly.

In this form, a pair of guard, guide, or support members 28 and 29 are shown attached to the bracket 23, the upper member 28 preferably being of resilient structure and disposed inwardly as the member 11 in Figure 2 for engaging suitable bearings on the associated beams. The lower member 29 may be of rigid structure for reinforcing the upper member and may extend di-

rectly beneath the brake beams as a safeguard therefor.

The form in Figure 4 is, in general, similar to that in Figure 3 except that the bracket 38 is provided with coextensive jaws 31 receiving the inner extremity of the channel horizontal web 32 and secured thereto by rivets 33. The jaws 31 support the guard, guide, or support bracket, as in Figure 1, independently of the attaching rivets 33.

In Figure 5, the flanged bracket 34 for the guard, guide, or support member (not shown) is attached to the horizontal web 35 of the bolster spring seating channel by means of rivets 36 and lip 37 integral with the guard, guide, or support bracket and hooked over the inner extremity of web 35. No side frame tie bar is provided, as in Figures 3 and 4, and the outer extremity of the horizontal web 38 on the side frame member 39 is provided with a lip 40 hooked through the recess 41 in the body of the spring seat web 35 for maintaining the channel member and guard, guide, or support in position in case the bolster springs (not shown) are removed.

In Figures 6 and 7, the bracket 42 is attached to the spring seat channel 43 by the rivets 44. A lip 45 punched from the body of the web portion 46 of the spring seat channel is hooked through a recess 47 in the side frame horizontal web 48 for maintaining the member 43 and bracket 42 in position.

Figure 8 illustrates a special form of spring seat channel 49 having the flanged brake beam guard, guide, or support bracket 50 and the lug 51 for attachment of the tie bar 52 formed integral therewith. A vertical rib 53 reinforces the inner portion of the spring seat channel above the bracket 50.

The horizontal web portion 54 of the channel member includes the bosses 55 for positioning the bolster springs, and the elements 56 and 57 cooperate with corresponding recesses in the side frame horizontal web member 58 for positioning the channel member. At the outer extremity of the channel member 49 is a hook 59 extending around and beneath the outer extremity of the framing web 58 and preventing tilting of the channel member 49 due to the weight of the guard, guide, or support structure at the inner end thereof in case the bolster springs (not shown) and the tie bar 52 are removed.

In Figures 9 and 10, the truss-type brake beams 60 are safeguarded by means of a rod 61 secured to the beams by clips 62 and extending above the hooked inner extremity 63 of the spring seating channel 64 which portion is bent to cooperate with rod 61. Rod 61 also mounts coil springs 65 functioning as brake beam releases. A lip 66 at the outer extremity of the horizontal web portion 67 of the channel 64 is bent around and beneath the corresponding portion of the framing horizontal web 68. The type of brake beam safety guard illustrated in Figures 9 and 10, aside from the especially formed channel member 64, does not constitute the present invention. Any suitable brake beam guard, guide, or support device may be provided. If desired, the hook element 63 may be separately formed and secured to the inner end of the spring seating member.

In Figure 11, the inner extremity of the horizontal web portion 69 of the spring seating channel 70 is bent downwardly at 71 and cooperates with an angle 72 secured to the web 69 by rivets 73, or other suitable means, to form a flanged bracket for mounting the brake beam guard,

guide, or support members 74 therebetween. The outer extremity of spring seating web 69 is hooked downwardly around the framing web 75, as in Figure 10.

In Figures 12 and 13, the inner extremity of the horizontal web portion 76 of the spring seating channel 77 is doubled outwardly upon itself, as at 78, for gripping the brake beam guard, guide, or support strap 79, the assembly being maintained by the vertical pins 80. The channel member 77 is stabilized by the hook 81.

In Figure 14, the bolster spring seating channel 82 is provided with a downwardly bent angle 83 forming a bracket for mounting the angular brake beam guard, guide, or support member 84. Tie bars, as at 85, are hooked into the spring seating channel at the sides of the bracket portion 83.

In Figure 15 the brake beam guard, guide, or support angle 86 is resiliently supported by coiled springs as that at 87 carried by the bolt 88 depending from the inner extremity of the horizontal web portion of the bolster spring seating channel 89.

In Figure 16, the channel member 90 does not directly support the brake beam guard, guide, or support, or its bracket, as in the previous structures. Formed integral with the flanged bracket 91 is the horizontal web 92 resting on top of the horizontal web portion 93 of the channel member 90 and constituting a seat for the bolster springs (not shown). Also formed on the integral spring seat and bracket structure is the reinforcing rib 94 and lug 96 for attachment of the tie bar 97. The outer extremities of the webs 92 and 93 and the framing web 98 are secured together by a U-shaped clip or bracket 99 riveted in place. The clip 99 holds the members 90, 91 and 93 in position in case the bolster springs (not shown) are removed as do the hooked lips in various forms previously described.

Figure 17 shows a resilient brake beam guard, guide, or support strap 100 reinforced by the rigid angle safety guard 101, both being carried from the inner extremity of the horizontal web portion 102 of the bolster spring seating channel 103 by means of a U-shaped clip 104 similar to the clip 99 in the previous figure. The clip 104 is secured in position by rivets 105.

In Figure 18, the flanged bracket 106 is riveted to the inner extremity of the horizontal web portion 107 of the spring seat channel 108, the channel being stabilized by a clip 109 embracing the outer extremities of the web 107 and framing web 110. The clip in this form is bolted in position.

In most of the forms, the end portion of a cut-off spring plank of ordinary form may be utilized as the channel spring seating member and for carrying the brake beam guard, guide, or support device, while in others a special spring seat member is provided. Also in most of the forms hook means is provided for stabilizing the bolster spring seat against a tendency to tilt due to the overhanging weight of the break beam guard, guide, or support device. In Figures 1 to 5, in particular, at least a portion of the weight of the guard, guide, or support device is carried by a special lip or jaw formed on the guard, guide, or support bracket and overlying the supporting truck part. In Figures 9 to 14, inclusive, the cut-off spring plank is itself specially shaped to form all or a part of the mounting for the brake beam guard, guide, or support member.

The invention is not limited to the structures

illustrated and described but may be modified in various respects as will occur to those skilled in the art, and the exclusive use of all such modifications as come within the scope of the appended claims is contemplated.

5 I claim:

1. In a railway truck, a part having a web member, brake gear safety guard support structure including a member extending over said web member substantially across said part, one of said members including upwardly and downwardly facing elements receiving between them a part of the other of said members for maintaining the assembly of said members irrespective of additional securing elements.

10 2. In combination, railway truck side framing having a web member, a bolster spring seat member on said web member and extending a substantial distance inwardly from said framing, a brake gear guard, guide, or support structure at the overhanging inner portion of said member, and means spaced from the inner edge of said framing and extending from one of said members and hooked around an edge of the other 15 member for securing said members together.

20 3. In a railway truck, a side framing member including a horizontal web, a projecting bracket resting on said web and terminating a short distance inwardly of said web, and a brake beam 25 guard, guide, or support device secured to said projecting bracket and having a lip interlocked with said web to assist in supporting the weight of said bracket.

30 4. In a railway truck, side framing including a horizontal web, a projecting web member seated on said framing web and terminating a short distance inwardly of said framing, and a brake beam 35 guard, guide, or support device carried beneath said projecting member and having lip elements respectively overlapping the extremities of said framing web and said projecting web for supporting said device.

40 5. In a railway truck, framing including a horizontal web member, a second web member resting on and extending across said framing member and projecting horizontally therefrom, a brake beam guard, guide, or support bracket on the overhanging portion of said second web member, and means on one of said web members extending 45 around and overlapping a portion of the other for maintaining the assembly of said web members.

50 6. In a railway truck, framing including an opening for a bolster spring and having a horizontal web member at the bottom of said opening, a bolster spring seat member resting on said web member and projecting a short distance inwardly thereof, brake beam guard, guide, or support means carried on the overhanging portion of said spring seat member, one of said members having upwardly and downwardly facing elements engaging oppositely facing elements of the other member to maintain said members assembled with each other when the bolster springs are removed.

65 7. In a railway truck, side framing including a bolster spring receiving opening having a horizontal web member at the bottom thereof, a separate web member resting on said framing web member and having a projecting part terminating a short distance inwardly of the truck from said framing, and a brake gear safety guard device carried by said projecting part, one of said web members having a lip spaced outwardly of the truck from the inner portion of said side

framing and hooked around an edge of the other web member to maintain said web members assembled when the bolster springs are removed.

8. In a railway truck, side framing having a bolster spring receiving opening and a web portion at the bottom of said opening, the end portion only of a cut-off spring plank seated on said web portion and having an inwardly projecting part, and brake gear safety guard device carried by said projecting part, one of said portions having a lip interlocked with the other to maintain said spring plank portion in position.

10 9. In a railway truck, side framing having a bolster spring opening and a horizontal web at the bottom of said opening, a spring seat member seated on said web portion and projecting inwardly thereof, and brake gear safety guard means carried on the overhanging inner part of said spring seat member, the outer extremity of said framing web portion having a lip element 15 bent upwardly around and over the adjacent edge of said spring seat member so as to maintain said member in position when the bolster spring is removed.

20 10. In a railway truck, side framing having a bolster spring opening and a horizontal web at the bottom of said opening, a spring seat member seated on said web portion and projecting inwardly thereof, and brake gear safety guard means carried on the overhanging inner part of 25 said spring seat member, the outer extremity of said member including a lip element bent around and beneath the adjacent edge of said framing web portion to maintain said member in position when the bolster spring is removed.

30 11. In a railway truck, a side frame and a spring seat resting thereon and comprising a channel section with its web of greater length than its flanges and forming a hook-like element at the inner side of said frame, and a brake gear safety guard device including means directly associated with the inner end of said spring seat, said spring seat element constituting at least a part of said device.

35 12. In a railway truck, side framing having a bolster spring receiving opening and a web portion at the bottom of said opening, and the end portion only of a cut-off spring plank resting on said web portion, said spring plank portion having an inner end part bent over to form brake beam guard, guide, or support structure, and the outer part of one of said portions having a lip element interlocked with the other of said portions to maintain said spring plank portion in position.

40 13. A truck bolster spring seat member of channel section with its web projecting beyond its flanges and having a downwardly bent element at its inner end, and an angular element secured to said member adjacent said bent element and forming therewith a bracket with spaced flanges for receiving between them a brake beam guard, guide, or support member therebetween, said elements being apertured for receiving a guard, guide, or support holding pin.

45 14. Means for mounting a brake gear guard, guide, or support device on a railway truck side frame part comprising a member arranged for carrying said device at an end portion thereof, said member being arranged to extend across a horizontal web on the supporting truck part and having a return bend hook element for receiving the outer edge portion of said truck web to secure said member in position.

50 15. In a railway truck, side framing including

75

a horizontal web, a bolster spring seat member resting on said framing web and terminating a short distance inwardly of said framing, a bracket directly secured to said spring seat member and having a jaw interlocked with said framing member to assist in supporting the weight of said bracket, and a brake beam guard, guide, or support strap secured in said bracket.

16. In a railway truck, a frame including a supporting part having a web-like horizontal member, a spring seat member resting on said horizontal member and extending inwardly therefrom a substantial distance, a brake beam guard, guide, or support structure carried by the inner end of said seat member, and elements on one of said members engaging opposite sides of the other of said members to retain said seat member in position against the weight of said structure irrespective of other securing means.

17. In a railway truck, side frames, rigid brackets projecting from said side frames for mounting

brake gear guard, guide or support devices, and a tie member extending between the brackets on said side frames and pivotally connected thereto.

18. In a railway truck, side frames each having a spring seat structure, a brake gear guard, guide or support device carried by each of said structures, and a tie member extending from side to side of the truck and pivotally connected to said structures.

19. In a railway truck, spaced side frames, individual elements rigid with said side frames respectively for mounting respective brake gear guard, guide or support devices, and a tie member extending between said elements and pivotally connected thereto.

20. In a railway truck, spaced side frames, brake gear guard, guide or support devices attached thereto, and a tie element extending between said devices and pivotally connected thereto.

EDWIN G. BUSSE.
